(57) **CLAIM**

The ornamental design for a lollipop, as shown and described.

DESCRIPTION

FIG. 1 is a side elevational view of a lollipop showing our new design;

FIG. 2 is a top plan view thereof;

FIG. 3 is a bottom plan view thereof; and,

FIG. 4 is a bottom and side perspective view thereof.

The design is characterized by a cavity in the bottom of the ball, into which cavity the stick is inserted eccentrically.
